UNITED STATES PATENT OFFICE.

HENRY C. DIEFENBACH, OF DAYTON, OHIO.

DESIGN FOR A TOY BLOCK.

58,462.

Specification for Design.

Patented July 26, 1921.

Application filed April 22, 1921. Serial No. 463,681. Term of patent 14 years.

To all whom it may concern:

Be it known that I, HENRY C. DIEFENBACH, a citizen of the United States, residing in Dayton, Ohio, have invented a new, original, and ornamental Design for a Toy Block, of which the following is a specification, reference being had to the accompany-

ing drawing, forming part thereof, in which the figure is a perspective view of a toy block illustrating my new design.

I claim:

The ornamental design for a toy block, substantially as shown.

HENRY C. DIEFENBACH.
